UNITED STATES PATENT OFFICE.

EDWARD A. SWIFT, OF SEATTLE, WASHINGTON.

LOADING AND UNLOADING APPARATUS.

1,032,568.

Specification of Letters Patent. Patented July 16, 1912.

Application filed April 10, 1911. Serial No. 620,158.

To all whom it may concern:

Be it known that I, EDWARD A. SWIFT, a citizen of the United States of America, and a resident of the city of Seattle, in the county of King and State of Washington, have invented certain new and useful Improvements in Loading and Unloading Apparatus, of which the following is a specification.

10 My invention relates to apparatus for loading or unloading vessels and it has for its primary object the provision of a novel construction and arrangement of parts through the medium of which the operations 15 of loading and unloading can be carried on with rapidity and with a minimum expenditure of power.

A further object resides in the provision of one or more adjustable approaches projecting from the sides of the paths of travel of the elevators and providing the temporary support for the material or freight in being hauled between the ship and the wharf.

25 Other objects will be set forth as my description progresses, and those features of construction, arrangements and combinations of parts on which I desire protection, succinctly defined in my annexed claims.

30 Referring to the accompanying drawings, wherein like numerals of reference indicate like parts throughout the several views: Figure 1 is a vertical cross section of a hull of a ship equipped with my loading and un-

35 loading apparatus, portions thereof being broken away. Fig. 2 is a fragmentary longitudinal section thereof with portions removed, and Fig. 3 is a fragmentary plan of the apparatus.

40 In carrying out my invention I provide cars 1 and 2 supported for vertical movement in suitable shafts, which as now considered extend down into the hold of the ship's hull and comprise essentially vertical track members 3 which are connected at their upper end portions with suitable cross bars 4 extending between the upright members 5, which latter support suitable approaches 6 for vertical adjustment, as hereinafter more clearly set forth.

Reference numerals 7 and 8 indicate endless cables connected with elevators 1 and 2 respectively and with respective operating drums as 10, through the medium of which

55 the elevator cars can be raised and lowered. Cable 7 takes over suitable idlers or pulleys

7', 7" disposed at the opposite end portions of the elevator shaft, and cable 8 is engaged with similar idlers 8', 8". Cables 7 and 8 are given a number of turns on their drums 10 to thereby obtain the desired frictional engagement therewith, and in operation, the cable will therefore pay out from one side as drawn in from the other, as will be readily understood.

60 Reference numeral 11 indicates a motor, as for example, a reversible electric motor, with which a drive shaft 12 for the drums 10 is connected.

65 Drums 10, one of which is fixed to shaft 12 and the other to an adjacent shaft 12', are releasably connected by a suitable clutch, 13 whose movable clutch part 13' is splined to shaft 12' for movement into and out of engagement with the co-operating fixed 70 clutch part on shaft 12. Through the provision of clutch 13, shafts 12 and 12' can be driven simultaneously, or shaft 12 can be driven alone. This is an important feature of, my invention inasmuch as I am 75 thereby enabled to set the cars 1 and 2 for a longer or shorter travel.

It will here be explained that the cars 1 and 2 are substantially equal in weight, so as to balance one another, and that the cables 80 7 and 8 are wound on their drums 10, one in a reverse manner to the other so that with clutch 13 engaged power applied to shaft 12 operates the cars simultaneously in opposite directions.

90 Approaches 6, which are slidably supported on upright members 5 are raised and lowered through the medium of suitable lines 14, passing over sheaves 15 and having their free end portions engaged with cleats 16. Approaches 6 are provided at their outer end portions with hinged sections 6', which latter are preferably provided with rollers 6" for engagement with the wharf, and secured by flexible connections 17 against lowering movement.

95 Flexible connections 17 are conveniently in the form of chains and the links thereof are engaged with one or another of suitable pins or hooks 18 provided on upright members 5, as shown.

100 In operation, one or the other of the approaches 6, this depending on the particular side of the ship which faces the wharf, is adjusted so as to be positioned substantially as shown in Fig. 1 with its hinged outer section 6' resting on the wharf and

held by the flexible connection 17 to be thereby held against lowering movement upon listing of the ship. In thus holding the approach section 6', all danger of its 5 catching on the wharf and being wrenched or otherwise damaged upon the ship righting itself, is obviated. With the approach adjusted, motor 11 is operated to drive cars 1 and 2 until car 1 is at the lower limit of 10 its movement. Clutch 13 is now released or operated to disconnect shaft 12' after which motor 11 can be operated to move car 2 to the level of approach 6, and the clutch then engaged to connect the shafts 12 and 15 12' for simultaneous movement.

Cars 1 and 2 extend transversely of the ship's hull for substantially the entire space between the approaches 6, the latter being common to both cars and projecting inwardly with respect to the hull a desired 20 distance. By this arrangement the elevator shafts lie inwardly of the sides of the hull thereby providing spaces for reception of freight. This object of distributing the 25 weight of the cargo is further carried out through the provision of the releasable driving connection or clutch 13, which latter enables car 2 being lowered and left so during the final part of the loading operation, at which time car 1 is operated alone 30 and the cargo lowered thereby placed on and about the car 2 and in its shaft.

Cars 1 and 2 can be of any suitable construction, I prefer however, to provide the 35 same with elongated shoes or track engaging parts 20. Similar shoes or engaging parts, as 21, are also provided for the approaches 6, as shown.

Various changes can be made in the 40 minor details of construction without departing from the spirit of my invention as defined in my annexed claims, and further, it is to be understood that my loading and unloading apparatus is not limited in application to vessels, as it is equally adaptable for arrangement on docks or scows.

Having thus described my invention what I claim as new, and desire to secure by Letters Patent of the United States of America, is:

1. In apparatus of the character described, two cars, means supporting said cars for vertical movement, a vertically adjustable approach common to said cars, 55 means for simultaneously operating said cars in relatively opposite directions, and a releasable connection between one of said cars and said operating means, whereby the other of said cars can be operated independently.

2. In apparatus of the character described, two cars, means supporting said cars for vertical movement, an approach ar-

ranged at the side of the path of said cars for adjustment lengthwise thereof, means 65 for operating said cars including a pair of drums and cables engaged with said drums and each connected with a respective car, means for operating said drums simultaneously, and a releasable connection between 70 said drums.

3. In apparatus of the character described, two cars, means supporting said cars for vertical movement, an approach arranged at the side of the path of said cars, 75 means for adjusting said approach vertically, means for operating said cars simultaneously in relatively opposite directions including a pair of drums and cables engaged with said drums and each connected 80 with a respective car, means for operating said drums simultaneously, and a releasable connection between said drums.

4. In apparatus of the character described, two cars, means supporting said 85 cars for vertical movement, operating means for said cars connecting the same for lowering of one car simultaneously with the elevating of the other, and an approach supported at the side of the path of said cars 90 for vertical adjustment.

5. In apparatus of the character described, in combination with a float, two cars extending transversely of said float and arranged side by side lengthwise of 95 said float, means supporting said cars for vertical movement, means for operating said cars, and vertically adjustable approaches on said float on opposite sides of said cars.

6. In apparatus of the character described, in combination with a float, two cars arranged side by side lengthwise of said float, means supporting said cars for vertical movement, means for operating 105 said cars, approaches on opposite sides of said cars, swingingly mounted outer sections for said approaches projecting beyond the adjacent sides of said float, and means for securing said outer sections of the approaches against downward movement.

7. In apparatus of the character described, in combination with a float, a car, means supporting said car for vertical movement, means for operating said car, an 115 approach, means supporting said approach for vertical adjustment at the side of the path of said car, means for adjusting said approach.

Signed at Seattle, Washington this 28 120 day of March 1911.

EDWARD A. SWIFT.
